MERCHANDISE DISPLAY STAND

William S. Leath, 1904 Highfield Drive,
Birmingham, Ala. 35216

Filed Apr. 11, 1974, Ser. No. 459,894

Term of patent 14 years

Int. Cl. D20—02

U.S. Cl. D6—85

Fig. 2

Fig. 1

Fig. 3

Fig. 4

Fig. 5

FIG. 1 is a front elevational view of a merchandise display stand showing my new design;

FIG. 2 is a top plan view thereof;

FIG. 3 is a side elevational view taken along the lines 3—3 of FIGS. 1 and 4; the side of each stand not shown is identical to the side shown and the rear of each stand is plain and unornamented;

FIG. 4 is a front elevational view, drawn to a smaller scale, showing a modified form of my new design wherein the width of the stand is twice the width of the stand shown in FIGS. 1 and 2; and

FIG. 5 is a top plan view of the stand shown in FIG. 4.

I claim:

The ornamental design for a merchandise display stand, as shown and described.
